C. S. RAILSBACK

MEANS FOR PREVENTING FRAUDULENT MANIPULATION OF CAR SEALS

Filed Aug. 6. 1921

INVENTOR.
Chas. S. Railsback

BY
G. J. Gleannan
ATTORNEY.

UNITED STATES PATENT OFFICE.

CHARLES S. RAILSBACK, OF COLORADO SPRINGS, COLORADO.

MEANS FOR PREVENTING FRAUDULENT MANIPULATION OF CAR SEALS.

Application filed August 6, 1921. Serial No. 490,277.

To all whom it may concern:

Be it known that I, CHARLES S. RAILSBACK, a citizen of the United States, residing at Colorado Springs, in the county of El Paso and State of Colorado, have invented certain new and useful Improvements in Means for Preventing Fraudulent Manipulation of Car Seals, of which the following is a specification.

This invention relates to means for preventing fraudulent manipulation of car seals, and its principal object is to provide in operative relation to a fastening of the type used on railway car doors, an appliance of simple construction which prevents the restoration of a seal applied to said fastening to a locked condition after it has been broken or has otherwise been opened, with evil intent.

It is a well-known fact that railroad companies and shippers are continually subject to losses owing to the theft of merchandise from cars after the doors have been sealed at the place of loading.

The devices most commonly used for the purpose of sealing the car door consist of a lock enclosed in a housing securely fastened at the end of a strap of pliable metal. The housing has an opening to receive the free end of the strap after it has been passed through an aperture of a fastening of the hasp and staple type commonly used on doors of railroad cars, and its strap upon entering the housing is engaged by the locking means concealed therein which automatically secures it against withdrawal.

It is a frequent occurrence that before a car thus sealed reaches its destination, part of its contents are stolen by persons who have the cunning of opening the seal and then restoring it to a condition which prevents discovery of its having been tampered with, without close and careful inspection.

Principal among these method of fraudulent manipulation of the seal are breaking of the housing in which the lock is concealed and subsequently refastening the severed parts thereof, or cutting the strap and later restoring its continuity by bending the ends of its severed parts upon each other or by hooking one of said ends into the aperture of the lock housing.

The last described methods obviously necessitate a reduction in the length of the strap and the other method requires ready access to the housing of the lock by which

the ends of the strap are secured, and it will therefore be evident that if means are provided which prevent shortening of the strap after it is applied to the door fastening and which cover the lock housing so as to render it inaccessible for fraudulent manipulation, destruction, and consequent reparation of the seal by any of the above described methods is effectively prevented and any attempt to gain access to the car by breakage of the seal is readily detected.

It is upon the principle of protecting the seal by the above stated preventive measures that the present invention is based, and I desire it understood that while in the accompanying drawings my invention has been shown as applied to a particular type of fastening, it may be effectively employed in connection with fastenings of different construction by immaterial variations in the form and arrangement of its parts, falling well within the scope of the invention as defined in the hereunto appended claims.

In the drawings in the several views of which like parts are similarly designated,

Figure 1 represents a face view of a hasp and staple lock of a freight car door showing my invention in operative relation to a seal by which the parts of the fastening are connected;

Figure 2, a section on the line 2—2, Figure 1 drawn to an enlarged scale;

Figure 3, an enlarged transverse section along the line 3—3, Figure 1, and

Figure 4, a fragmentary section taken on the line 4—4, Figure 2.

Referring more specifically to the drawings the reference numerals 2 and 3 designate respectively the staple and the hasp of the fastening, which are held together by a sliding bolt 4. The staple projects from a plate 5 by means of which it is fastened to the door frame of the car, and the hasp is pivotally attached to the car door by a staple or eye bolt 6 passing through an aperture at one of its ends.

The hasp has at its free end an eye to receive the staple of the fastening and the plate to which the staple is attached has a slideway 7 for the up and downward movement of the bolt.

The bolt which normally extends in an opening of the hasp, has a forwardly projecting lip 8 above and in close proximity to the staple 2 and it has at its upper end a head 9 of sufficient weight to retain it

in its locked position by the force of gravity.

The lip of the bolt and the hasp have registering slots 2^a and 8^a for the passage of the strap of the seal which in its entirety 5 has been designated by the reference character 10.

The fastening so far described is one commonly used on freight cars and the seal shown in the drawings and hereinafter to 10 be described, is of a type universally adopted by railroads throughout the country, as a protection against pilferage of the contents of their cars.

The seal consists of a lock enclosed in 15 a housing 12 of spherical form, which is usually made in two sections connected by a circumferential bead. A strap 13 of pliable metal is permanently fastened at one end inside the housing and the latter has 20 an opening 14 to admit the free end of the strap to the lock.

The application of my invention to a 25 fastening of the type shown in the drawings and herein described requires the elongation of the locking bolt for the purpose of increasing the distance between its head and the staple, socketing of the head of the bolt to provide a pocket 15 for the locking element of the seal and widening 30 of the slot 8^a in the lip of the bolt for a purpose which will later be explained.

The distance between the head of the bolt and the staple of the fastening when the bolt is in its locked position, is such that 35 the strap of the seal when doubled through the slot of the staple and fastened by the lock within the pocket of the bolt head, is taut and prevents any slack or play which might permit of its being shortened in the 40 manner and for the purpose hereinbefore explained.

The pocket 15 provided by the socketed 45 head of the bolt, is of sufficient depth and diameter to admit the locking element of the seal when entered at the top thereof. Its lower portion is offset to one side, as shown in Figure 4, to prevent access to the 50 circumferential bead which connects the sections of the housing, by the insertion of a pointed or sharp edged tool, and its bottom has a slot 16 for the passage of the two parts of the doubled strap.

The object of increasing the width of the 55 slot 8^a in the lip of the bolt is to prevent of the strap being held in place by a wedge driven through the registering slots of the staple and the lip after it has been cut at a point between or in close proximity to these parts.

60 It will be apparent that with a seal thus arranged its fraudulent manipulation without detection is practically impossible. The pocket provided by the socketed head of the bolt, protects the locking element of the seal so as to positively prevent its being

opened and subsequently repaired, even by the use of specially constructed tools such as are often employed by dishonest manipulators of the seals; the stretched condition of the strap frustrates any attempt to remove the seal and then repair it to even a semblance of its locked condition by shortening the same, and the enlargement of the slot in the lip of the locking bolt prevents fastening of the strap by means of a wedge 75 as hereinbefore explained.

It will be readily understood from the above description of the advantages of the invention that it may be employed in connection with fastenings which differ in construction from that shown in the drawings, even to the extent of eliminating the locking bolt, it being evident that its essential requirement is the provision of a protective pocket for the locking element of the seal 80 at a distance from the part of the fastening engaged by the loop of the strap of the same, which necessitates of the strap being drawn taut between the fastening and the pocket to bring it in operative engagement 85 with the lock inside the housing. 90

Having thus described my invention what I claim and desire to secure by Letters-Patent is:

1. The combination with a fastening and 95 a seal including a strap engaging with a part of the fastening and a lock securing the ends of the strap together, of a pocket adapted to receive the lock of the seal.

2. The combination with a fastening and 100 a seal including a strap engaging with a part of the fastening and a lock securing the ends of the strap, of means adapted to predetermine the extent of the strap between said part and the lock by engagement 105 with the latter.

3. The combination with a fastening, and 110 a seal comprising a doubled strap engaging with a part of the fastening and a lock adapted to secure an end of the strap, of a pocket for the lock of the seal, disposed relative to the part of the fastening engaged by the strap of the same, to necessitate of the strap being drawn taut between said part and the pocket for the operative 115 engagement of its end with the lock.

4. The combination with a fastening and 120 a seal including a strap engaging with a part of the fastening and a lock securing the ends of the strap, of a pocket adapted to receive the lock of the seal, and having an opening in its bottom to admit the strap of the same.

5. The combination with a fastening and 125 a seal including a strap engaging with a part of the fastening and a lock securing the ends of the strap, of a pocket adapted to receive the lock of the seal, and having an opening in its bottom to admit the strap of the same, the bottom portion of said 130

pocket being offset with relation to its outer portion through which the lock is entered.

6. The combination with a fastening comprising a hasp and an apertured staple, and
5 a seal having a doubled strap passing through the aperture of the staple and a lock securing an end of the strap, of a pocket for the lock arranged relative to the staple, to necessitate of the strap being
10 drawn taut between the staple and the pocket for the operative engagement of its end with the lock.
7. The combination with a hasp-and-staple fastening, and a seal comprising a strap engaging with a part of the fastening and a lock securing the ends of the strap, of a locking-bolt provided with a socketed head adapted to contain the lock of the seal, and having in the bottom of
20 its socket, an opening to admit the strap of the same.

8. The combination of a fastening comprising a hasp and an apertured staple, a car seal composed of a doubled strap passing through the aperture of the staple and a lock adapted to secure an end of the strap, and a locking bolt provided with a socketed head adapted to contain the lock of the seal and having in the bottom of its
25 socket, an opening to admit the strap of the same, said head being disposed relative to

the staple when the bolt is in its locking position, to necessitate of the strap being drawn taut for the operative engagement of its end with the lock.

9. The combination of a fastening comprising a hasp and an apertured staple, a car seal composed of a doubled strap passing through the aperture of the staple and a lock adapted to secure an end of the
40 strap, and a locking bolt having a lip provided with an aperture which registers with the aperture of the staple for the passage of the strap, and a socketed head adapted to contain the lock and having in the bottom of its socket, an opening to admit the strap.

10. The combination of a fastening comprising a hasp and an apertured staple, a car seal composed of a doubled strap passing through the aperture of the staple and a lock adapted to secure an end of the strap, and a locking bolt having a lip provided with an aperture of different width which registers with the aperture of the staple for the passage of the strap, and a socketed head adapted to contain the lock and having in the bottom of its socket, an opening to admit the strap.

In testimony whereof I have affixed my
signature.

CHARLES S. RAILSBACK.
